UNITED STATES PATENT OFFICE.

WILLIAM D. COOLIDGE, OF SCHENECTADY, NEW YORK, ASSIGNOR TO GENERAL ELECTRIC COMPANY, A CORPORATION OF NEW YORK.

CATHODE-RAY DEVICE.

1,211,091.

Specification of Letters Patent. Patented Jan. 2, 1917.

Application filed September 8, 1913, Serial No. 788,566. Renewed September 28, 1916. Serial No. 122,314.

To all whom it may concern:

Be it known that I, WILLIAM D. COOLIDGE, a citizen of the United States, residing at Schenectady, county of Schenectady, State 5 of New York, have invented certain new and useful Improvements in Cathode-Ray Devices, of which the following is a specification.

The present invention relates to the construction of X-ray or vacuum discharge tubes operating with a pure electron discharge independent of gas ionization, and it comprises certain novel structural details in tubes of the type such as described in my 15 prior application, Serial No. 766,549, filed May 9, 1913.

In accordance with one feature of my present invention the current-carrying capacity of the tube with a given cathode temperature and voltage has been materially increased by arranging the heated, electron-emitting part of the cathode in one plane, for example, by coiling it in the form of a flat spiral.

25 My invention will be best understood by reference to the following description taken in connection with the accompanying drawings, in which—

Figure 1 is an outline drawing of the tube 30 as a whole showing the relation of the various parts, and Fig. 2 is an enlarged view of the electrodes.

The inclosing envelop 1 of the X-ray tube consists of a material pervious to X-rays, for 35 example, of a lime glass known on the market as German glass, and is provided with an anode 2 and a cathode 3. The cathode may be said to consist of two parts, a heated portion 25, and an unheated part 21, as will 40 be hereinafter more fully described. The heated part of the cathode consists preferably of ductile tungsten although other highly refractory material, for example, tantalum may likewise be used. The tube 45 21 may consist of either molybdenum or tungsten. The stem 4 of the anode is attached by means of a tungsten or molybdenum wire 5 to a rod 6 which may consist of molybdenum and which passes through a

tubular extension 7 of the tube. The end 50 of the rod 6 is attached by means of a wire 8, consisting conveniently of molybdenum, to a platinum leading-in wire 9. The tubular extension 7 of the anode end of the bulb and a similar tubular extension 10 of the 55 cathode end serve to increase the distance between the terminals. The rod 6 is welded or riveted to a number of split cylindrical tubes 11 of refractory metal, preferably molybdenum, which serve to both support 60 the anode rod and conduct heat away from it to the glass so as to protect the seal. These cylindrical supports, most conveniently are made of resilient metal so as to grip the inner surface of the glass even though it is 65 somewhat uneven.

The cathode end of the tube is provided with an inwardly projecting stem 12, the tip of which consists of some suitable heat-resisting insulating material, for example, 70 of a heat resisting glass, such as a sodium-magnesium boro-silicate known on the market as low expansion glass, or even of quartz. This tip may be joined by means of a graded seal consisting of a series of short sections 75 of glasses, indicated at 8, to a section 13 consisting of lime glass the same as the rest of the tube. The thermal coefficient of expansion of the sections intervening between the two materials increases progressively when 80 passing from the material of lower coefficient to the material having the higher coefficient. Such intermediate glasses may be made by mixing the two materials to be joined. The conductors 14, 15, which supply 85 heating current to the cathode are embedded in the stem 12 and are attached respectively by copper wires 16, 17, to platinum leading-in conductors 18 and 19, joined thereto by welding. A glass tube 20 surrounding the wire 19 serves to insulate the wires 18 and 19 from each other. The cathode may be heated by attaching the conductors 18, 19, to a suitable insulated source 90 of energy, such as a storage battery, (not 95 shown in the drawing).

The tube 21 surrounding the heated part of the cathode is attached to and supported

by wires 22, 23, also embedded in the tip of the stem. The tube 21 serves to focus the cathode rays upon the anode and for this purpose is preferably brought to the same potential as the cathode by electrically connecting it to the cathode by means of a small tungsten or molybdenum wire 24. It also prevents a discharge of electricity from the heated part of the cathode in a direction 10 away from the anode.

As fully set forth in my copending application, a tube of the general character above described operates independently of gas ionization, the current being carried by negative charges called electrons emitted from the heated cathode and moving under the influence of the impressed electromotive force from the cathode across the evacuated space to the anode. In order that the current may be carried by the electrons entirely independently of positive ions resulting from ionization of gas molecules, the tube is exhausted to a very high degree, in the neighborhood of a few hundred thousandths of a millimeter of mercury pressure, and the electrodes are completely freed from gas, by both subjecting them to a high temperature and also to the gas-freeing influence of the cathode discharge itself during 30 exhaust.

As already mentioned the cathode discharge is focused upon the target by the conductive ring or cylinder 21, which so modifies the static field in the tube as to 35 direct the electrons upon a spot of limited area. I have found that when the cathode is given a linear extension in a direction parallel with the axis of the focusing member that only the tip of the cathode is effective to furnish electrons to carry the current. When the filament, for example, is given the shape of a helix or loop, the static field of the filament near its tip appears to 40 repel the electrons from the other parts of the filament back of the tip which are further removed from the anode than the tip. Hence the electrons carrying the current are furnished largely by the tip. This has the effect of greatly limiting the amount of 45 current which can be transmitted through the tube with a given filament temperature and at a given voltage.

I have found that by disposing the cathode in a plane substantially normal to the axis passing through the focusing device and the anode, the discharge current may 50 be very materially increased. Such a shape may be conveniently given to the cathode by coiling the cathode conductor 25 in the form 55 of a flat spiral although it is obvious that other shapes, for example, a zig-zag grid may be used with the same effect.

In the X-ray tube above described all exposed metal parts consist of either tungsten

or molybdenum which I have found may 65 be very completely freed from gas.

Another feature of novelty of the present form of X-ray tube is the location of the cathode 3, substantially near the center of the bulb, out of direct proximity to the 70 walls. I have found this location of the cathode to be advantageous due to the fact that when the cathode projects beyond the neck of the bulb, the discharge is less influenced by static charges on the glass, 75 which act to reduce the current. The diameter of the spiral as indicated in the drawing is less than the diameter of the working face of the anode.

What I claim as new and desire to secure 80 by Letters Patent of the United States, is:—

1. An electrical discharge tube comprising an envelop, an anode, a cathode adapted to be independently heated disposed substantially in a plane normal to a line passing through anode and cathode, and means for focusing the cathode discharge, said envelop and electrodes being freed from ionizable gas to such extent as to render 90 said tube operable with an electron discharge independent of gas ionization.

2. A cathode ray tube operable with an electron discharge independent of gas ionization, provided with a cathode having a 95 heated portion disposed substantially in one plane perpendicular to the axis of the tube and a static focusing ring surrounding said cathode.

3. In a Roentgen ray tube, operable with 100 an electron discharge independent of gas ionization, an anode, an electron-emitting cathode arranged in the shape of a flat spiral located perpendicular to the axis of the tube and having a diameter smaller than 105 the working face of the anode.

4. In an electron-discharge tube operable with a discharge independent of gas ionization, an anode, a cathode conductor consisting of a wire disposed substantially in a 110 plane perpendicular to an axis passing through the electrodes, means for heating said wire, and means for focusing the cathode rays upon said anode.

5. In an X-ray tube operable with an 115 electron discharge independent of gas ionization, an evacuated envelop pervious to X-rays, a stem having a tip of heat-resisting, insulating material projecting into said envelop, refractory supports joined to said tip, an anode and an electron-emitting cathode comprising a heated conductor and a surrounding ring of refractory conducting material carried by said supports.

6. An X-ray tube comprising an envelop 120 evacuated to such low pressure that positive ionization is substantially absent, an anode, an electron-emitting cathode project-

ing out of immediate proximity to the walls of said envelop, and means for focusing the cathode discharge.

7. An X-ray device comprising an evacuated envelop, an anode, a cathode comprising a closely wound spiral of wire, said spiral having a diameter smaller than the working face of said anode and located in a plane substantially perpendicular to a

line passing through the anode and cathode 10 and means for conducting a heating current to said cathode.

In witness whereof, I have hereunto set my hand this 5th day of September 1913.

WILLIAM D. COOLIDGE.
